OPHTHALMOSCOPE HEAD

Walter K. Long, Auburn, N. Y., assignor to Welch
Allyn, Inc., Auburn, N. Y., a corporation of
New York

Application August 20, 1951, Serial No. 16,380

Term of patent 14 years

(Cl. D57—1)

To all whom it may concern:

Be it known that I, Walter K. Long, a citizen of the United States, residing at Auburn, in the county of Cayuga and State of New York, have invented a new, original, and ornamental Design for Ophthalmoscope Head, of which the following is a specification, reference being had to the accompanying drawings, forming a part hereof.

Figure 1 is a view in front elevation as seen from the observer's side, of an ophthalmoscope head embodying my new design;

Figure 2 is a view in rear elevation;

Figure 3 is a view in side elevation; and

Figure 4 is a view in top plan.

I claim:

The ornamental design for an ophthalmoscope head, as shown.

WALTER K. LONG.
